LOCK

Robert B. Hayden, Seattle, Wash., assignor to
H. L. J. Specialty Co., Seattle, Wash., a corpora-
tion of Washington

Application January 26, 1932, Serial No. 588,948

6 Claims. (Cl. 70—14)

My invention relates to improvements in locks and the primary object of my invention is to provide a lock of extremely simple and cheap construction which is especially well adapted for use on small individual money banks of the form disclosed in my co-pending application Serial Number 585,034, filed Jan. 6, 1932 and in other like instances where the lock must be of small size and where economy of space and security are important.

Another object is to provide a lock which is strong and durable in construction, which has few parts and which is not liable to get out of order.

Another object is to provide a lock in which all of the parts are punched or stamped from metal and in which there are no springs or catches and on which there is no machine work thus greatly facilitating large quantity production of said lock.

A further object is to provide a lock in which the throw member is retained in position by friction but which is difficult to pick or tamper with.

Other and more specific objects reside in the novel construction adaptation and combination of parts hereinafter described and claimed.

In the drawing Figure 1 is a fragmentary plan view of a receptacle having a lock constructed in accordance with my invention installed thereon, the lock being shown by dotted lines.

Fig. 2 is a fragmentary sectional view through the lock substantially on broken line 2—2 of Fig. 1.

Fig. 3 is a fragmentary sectional view substantially on broken line 3—3 of Fig. 1.

Fig. 4 is a plan view of the lock with parts in section taken substantially on broken line 4—4 of Fig. 2.

Fig. 5 is a detached plan view of the lock throw. Fig. 6 is an edge view of the same.

Fig. 7 is a detached perspective view of the main frame plate of the lock.

Fig. 8 is a detached plan view of a spring washer used in the lock.

Fig. 9 is an elevation of a key used for operating this lock.

Like reference numerals designate like parts throughout the several views.

The drawing is made to a scale much larger than the lock will usually be in practice.

In the drawing I have shown my lock applied to a receptacle 10 of small size for locking a cover 11 on said receptacle. The lock is mounted on a plate 12 which is rigidly secured to the cover and is removable therewith.

The lock proper comprises a main frame plate 13 of greater length than width, stamped to form

a depressed portion or recess 14 which extends entirely across said frame plate. A circular depression 15 is provided centrally within the recess 14 and a small hole 16 is provided in the center of the depression 15. The length of the frame plate 13 is greater than its width and the ends thereof are split and portions 17 are bent upwardly to form rivet lugs. Other portions 18, at the corners, are allowed to project outwardly beyond the upwardly bent rivet portions 17 to form a more stable bearing against the plate 12 to which the said frame plate 13 is secured. Stop lugs 19 and 19' are bent upwardly at diagonally opposite corners of recess 14.

A throw member composed of a disc like portion 20 having a peripheral locking tongue 21 is rotatably disposed within the recess 14 and has a depressed annular central portion 22 which fits into the recess 15. A hole 23 is provided centrally within the depressed portion 22 and a segment 70 of the depressed portion 22, preferably approximately ninety degrees in arc, is cut away leaving an opening 24 having shoulders 25 and 26 at the respective sides thereof. Shoulders 27 and 28 are formed on the respective edges of the locking tongue 21 for engagement with lugs 19—19'. One corner of the locking tongue 21 is preferably depressed or beveled off as at 29.

A spring washer 30 is preferably provided for insertion between the bottom of the recess 15 and the throw member 20.

In assembling this lock the spring washer 30 is placed within the recess 15, the throw 20 is then placed on the spring washer 30 with the depressed central portion 22 protruding into the recess 15 90 whereby said throw is rotatably held but can not be displaced. The frame member 13 is then secured to the plate 12 by inserting the upwardly extending rivet portions 17 through slots located at 31 in said frame plate and riveting the same, 95 as better shown in Fig. 3. The portions 18 which extend beyond the rivet lug portions 17 give a more firm bearing or footing against the plate 12 and help to resist any tendency of the center portion of said frame 13 to spring away from the 100 plate 12. The spring washer 30 together with the resiliency inherent in the frame member 13 keep the throw member 20 pressed tightly up against the plate 12 at all times whereby it will be securely held frictionally and can not be turned except by 105 insertion of the proper key.

The throw member 20 is adapted to be moved rotatively by a key 32 having a lug 33 on its inner end for engagement with the shoulders 25 and 26 of said throw member 20. Two key hole 110

slots 34 and 35 arranged at right angles to each other are provided respectively in the cover 11 and in the plate 12 which lies directly over the lock. The keyhole slot 35 preferably is positioned so that the key lug 33 will be turned into a position of non-registration with this slot 35 when the lock throw tongue 21 is in the unlocked position. This makes it possible to use the key for lifting the lid after the lock has been unlocked, 10 the key lug then engaging with the plate 12. The recess 24 in the throw member 20 makes it impossible to move the throw member into such a position as to block insertion of the key because the recess 24 can not be turned out of registration with the keyhole slot 35 due to the action of the stops 19 and 19'. When the throw member is in the locked position and the key inserted rotation of the key in a clockwise direction will cause the key lug 33 to engage with the shoulder 20 26 and move the lock throw clockwise until the tongue member is positioned within the recess 14 in the frame member 13 and substantially in lengthwise alignment with said frame and the shoulder 28 on the tongue member strikes against the stop 19, which stop 19 limits the clockwise movement of the throw. To move the throw member from the unlocked to the locked position the key is turned in a counter-clockwise direction so that the key lug 33 will engage with the shoulder 25 and move the throw member 20 in a counter-clockwise direction until the shoulder 27 strikes against the stop plug 19' and the tongue 21 is securely locked beneath a fixed member 36 which is rigid with the receptacle 10. The depressed corner 29 of the tongue 21 facilitates the entrance of said tongue under the fixed member 36 and makes it possible to have frictional engagement of the tongue 21 with the member 36 without danger of the edge of the throw member striking against the member 36 and being blocked from engagement thereunder. The throw member 20 is frictionally held at all times and can not become loose enough to be accidentally disengaged and the lock is free from springs and catches thus 40 making it very cheap to build and easy to assemble. The two keyholes at right angles to each other make the lock more difficult of access for the purpose of picking.

50 The foregoing description and accompanying drawing clearly disclose a preferred embodiment of my invention but it will be understood that this disclosure is merely illustrative and that such changes in the invention may be made as are fairly within the scope and spirit of the following claims.

55 I claim:

1. In a lock, a main frame member having a 60 depressed portion therein and having a circular recess centrally positioned within said depressed portion, a plate secured to said main frame member, a disc like throw member having a circular depressed portion rotatively mounted in said depressed portion of said main frame member and having a locking tongue extending beyond the side 65 of said main frame member when in locked position, and a spring washer within said circular recess and in contact with said throw member whereby said throw member is frictionally held against said plate, said plate and said throw member being slotted for the reception of a key.

70 2. In a lock of the class described, a rotatably mounted disc like throw member, a locking tongue protruding from the periphery of said throw member and engageable with a fixed locking element, the corner of said locking tongue which first

engages said fixed locking element when said locking tongue is being moved to locked position being inclined to thereby afford wedge like engagement between said locking tongue and said locking element and spring means urging said throw member toward said locking element. 80

3. A lock, comprising a main frame member having a depressed portion intermediate its two ends which extends entirely across said frame member from side to side said frame member having a centrally positioned circular recess and said circular recess having a central hole therein, a plate against which the upper side of said frame member rests, means securing said frame member to said plate, said plate having a key-hole therein and a disc like throw member in said frame member having a peripheral locking tongue and having a central circular depressed portion which fits into the circular recess in said frame member, said circular depressed portion having an arcuate central key opening and having a cut away portion extending outwardly from said hole and arranged to be engaged by a key lug. 90

4. A lock, comprising a main frame member having a depressed portion intermediate its two ends which extends entirely across said frame member from side to side said frame member having a centrally positioned circular recess and said circular recess having a central hole therein, 100 stops extending upwardly at diagonally opposite corners of said depressed portion, a plate resting squarely against the upper side of said frame member and secured to said frame member, said plate having a keyhole therein, a disc like throw member in said frame member having a peripheral locking tongue and having a central circular depressed portion which fits into the circular recess in said frame member, said circular depressed portion having an arcuate central key 110 opening and having a cut away portion engaged by a key lug, the sides of said locking tongue engaging said stops on said frame member and limiting the rotary movement exerting a frictional pressure on said throw member. 115

5. A lock, comprising a main frame member of substantially greater length than width having a depressed portion intermediate its two ends which extends entirely across said frame member leaving arcuate walls at the ends of said depressed portion and leaving the sides of said depressed portion open, said frame member having a centrally positioned circular recess and said circular recess having a central hole therein, 120 stops extending upwardly at diagonally opposite corners of said depressed portion, rivet lugs extending upwardly near the ends of said frame member, a plate contacting squarely with the upper side of said frame and having recesses in which said rivet lugs are secured, said plate having a keyhole therein, and a disc like throw member in said frame member having a peripheral locking tongue and having a central circular depressed portion which fits into the circular recess in said frame member, said circular depressed portion having an arcuate central key 130 opening and having a cut away portion of substantially ninety degrees of arc extending outwardly from said hole and arranged to be engaged by a key lug, said cut away portion affording substantially ninety degrees relative lost motion between said throw member and the key the sides of said locking tongue engaging said stops on said frame member and limiting the rotary movement of said throw member. 135

6. A lock, comprising a main frame member of substantially greater length than width having a depressed portion intermediate its two ends which extends entirely across said frame member
 5 leaving arcuate walls at the ends of said depressed portion and leaving the sides of said depressed portion open, said frame member having a centrally positioned circular recess and said circular recess having a central hole therein, stops extending upwardly at diagonally opposite corners of said depressed portion, rivet lugs extending upwardly near the ends of said frame member, foot portions at each corner of said frame extending beyond said rivet lugs, a plate
 10 resting squarely against the upper flat side of said frame and having recesses in which said rivet lugs are secured, said plate having a key-
 15 hole arranged lengthwise relative to said frame, a disc like throw member in said frame member having a peripheral locking tongue and having a central circular depressed portion which fits into the circular recess in said frame member, said circular depressed portion having an arcuate central key opening and having a cut away portion of substantially ninety degrees of arc extending outwardly from said cut away portion affording substantially ninety degrees relative lost motion between said throw member and the key, the sides of said locking tongue engaging said stops and limiting rotary movement of said throw member, and a spring washer in the circular recess in said frame member exerting an upward pressure on said throw member.
